The ornamental design for an ornament for cremation and memorabilia container, as shown and described.

DESCRIPTION

FIG. 1 is a perspective view of our new, original and ornamental design for an ornament for cremation and memorabilia container;

FIG. 2 is a front view thereof;

FIG. 3 is a top view thereof;

FIG. 4 is a bottom view thereof; and,

FIG. 5 is an enlarged fragmentary cross sectional view taken along line 5—5 of FIG. 3 shown for clarity of illustration;

FIG. 6 is a top view of an alternative embodiment of our design;

FIG. 7 is a bottom view thereof; and

FIG. 8 is an enlarged fragmentary cross sectional view taken along line 8—8 of FIG. 6 shown for clarity of illustration;

FIG. 9 is a top view of yet another alternative embodiment of our design;

FIG. 10 is a bottom view thereof;

FIG. 11 is an enlarged fragmentary cross sectional view taken along line 11—11 of FIG. 9 for clarity of illustration;

FIG. 12 is a perspective view of still another embodiment of our design;

FIG. 13 is a top view thereof;

FIG. 14 is a perspective view of still another embodiment of our design;

FIG. 15 is a top view thereof;

FIG. 16 is a perspective view of still another embodiment of our design;

FIG. 17 is a top view thereof;

FIG. 18 is a perspective view of still another embodiment of our design; and,

FIG. 19 is a top view thereof.

The broken line showing of the word "indicia" in FIGS. 3 and 6, the sun dial face in FIG. 1, the gnomon in FIGS. 1 and 2, and the base in FIGS. 1 and 2 is for illustrative purposes only and forms no part of the claimed design.
